UNITED STATES PATENT OFFICE

105,847

DESIGN FOR A BRASSIÈRE VEST OR SIMILAR ARTICLE

Dorothea Doctors, New York, N. Y., assignor, by mesne assignments, to Dorothea Doctors and Sidney A. Fox, both of New York, N. Y., co-partners, trading under the firm name and style of "Dorothea Doctors"

Application May 2, 1936, Serial No. 62,423

Term of patent 14 years

To all whom it may concern:

Be it known that I, Dorothea Doctors, a citizen of the United States, residing in the county, city, and State of New York, have invented a new, original, and ornamental Design for a Brassière Vest or Similar Article, of which the following is a specification, reference being made to the accompanying drawing, forming a part thereof,

Fig. 1 is a front view of a brassière vest or similar article embodying the invention.

Fig. 2 is a rear view of a brassière vest or similar article embodying the invention.

I claim:

The ornamental design for a brassière vest or similar article substantially as shown.

DOROTHEA DOCTORS.
